UNITED STATES PATENT OFFICE.

OLIVER C. TALBOT AND ANDREW FLOOD, OF KANSAS CITY, MISSOURI.

MORTAR-MIXING MACHINE.

Application filed November 17, 1924. Serial No. 750,403.

To all whom it may concern:

Be it known that we, OLIVER C. TALBOT and ANDREW FLOOD, citizens of the United States, and residents of Kansas City, county of Jackson, State of Missouri, have invented a certain new and useful Improvement in Mortar-Mixing Machines, of which the following is a complete specification.

This invention relates to a machine for mixing mortar, plaster, cement and the like, and more especially to a structure whereby a quick-setting ingredient or material may be quickly, thoroughly and economically mixed with others and the discharge of the mixture effected with rapidity and completeness, it being characteristic of mortar, plaster and the like that if left in the mixing chamber, there will be a tendency to effect a setting of the next mix before the materials thereof have been transformed into a sufficiently homogeneous mass. Because of this fact one of the important features of the invention is to provide agitators which in effect, scrape the walls of the mixing chamber and thereby insure a thorough removal therefrom of all of the mix during the discharging or dumping operation.

Another important object is to produce a machine which quickly effects a thorough mixing of the materials in the interest of large capacity and economy of operation costs.

With these general objects in view, the invention consists in certain novel and useful features of construction and combinations of parts as hereinafter described and claimed; and in order that it may be fully understood, reference is to be had to the accompanying drawings, in which:—

Figure 1 is a side elevation of a mixing machine embodying the invention.

Figure 2 is a vertical section on the line II—II of Figure 1.

Figure 3 is a fragmentary section on the line III—III of Figure 1.

Figure 4 is an enlarged vertical section through the container of the machine.

Figure 5 is a section taken on the line V—V of Figure 4, and also shows a fragment of the frame work of the superstructure of the machine.

In the said drawing, 1 is a wheeled truck and 2 a traction bar or tongue. This truck or any other similar support should in its preferred form, be narrow enough to pass through an ordinary door opening and short

enough to be conveniently carried on an ordinary freight elevator so that it can be used on any floor of a building where it may be desirable to mix mortar or the like.

A skeleton superstructure for the truck comprises uprights 3 connected in pairs at their upper ends by cross beams 4, the respective side uprights being connected by longitudinal bars 5 and 5^a, the former being at the upper ends of the uprights and the bar 5^a, in a lower plane. Bearings 6 are mounted on the cross beams 4 for a pair of alined shafts 7 and 7^a, and journaled on said shafts is a tiltable cylindrical container 8 having a top opening and a flaring hopper 9, through which material is introduced into and discharged from the container.

A socket piece 10 is provided at one side of the container for a removable handle 11 by which the container is tilted, and said socket piece by engagement with bar 5 arrests the container when restored to normal position after each dumping or discharging operation. A pivoted catch 12 on the said bar, engages the socket piece to prevent accidental tilting in the direction necessary for dumping, and is tripped preliminary to the dumping operation. The bar 5^a limits movement in the last-named direction, as it stands in the path of the hopper, as shown by dotted lines in Figure 2.

Rotary agitators, of which shafts 7 and 7^a form parts, also comprise hubs 13 on said shafts, arms 14 extending radially from the hubs, and blades 15 secured to the outer ends of said arms. Preferably there will be two arms and blades for each agitator, each pair of blades respectively, being of form to, in effect, scrape one end wall and one half of the cylindrical body of the container in order that the entire mass of plastic mixture, as hereinafter referred to, may be stirred and mixed, and eventually expelled from the container. To accomplish the first of these results thoroughly and expeditiously, the blades at one end are set angularly with respect to the longitudinal axis of the container, so that they shall impart circular and endwise movement to the mass, the blades of one set moving the mass into the path of rotation of the blades of the other agitator, and to make this operation more efficient, the blades of one agitator are opposite the spaces between the blades of the other agitator, that is to say, the blades of one agitator occupy different radial planes

from those of the other. To accomplish the other object, the agitators are mounted on separate spaced shafts operated in reversed directions, one forcing the mass into the path 5 of rotation of the other and the latter turning in the proper direction to expel the mass through the opening when the container is tilted to dumping position, it being noted that, by reason of the scraping relation of 10 the blades to substantially the full interior area of the container and the omission of a full length shaft, a practically clean evacuation of the material is effected.

For operating the agitators as described, 15 the following mechanism is provided: 16 is a suitable motor mounted on the truck and provided with a driving cog pinion 17 meshing with a gear wheel 18 journaled on a longitudinal shaft 19 suitably mounted on the 20 truck. The gear wheel 18 has a clutch member 20 for engagement at times by a clutch member 21 keyed to rotate with and slide upon shaft 19, a conventional clutch-operating lever 22 being provided to slide clutch 25 member 21 into and out of engagement with clutch member 20. A gear pinion 23 on shaft 19 meshes with a gear 24 on a counter shaft 25. Shaft 25 has a sprocket wheel 26 connected to a large sprocket wheel on shaft 28 30 7, by a chain 27, and a sprocket wheel 28 on shaft 19 is connected to a large sprocket wheel 29 on shaft 7^a by a chain 30. The power-transmission mechanism described 35 imparts simultaneous rotation in opposite directions to the agitators when the motor is in operation and the clutch members are in engagement. When the clutch members are unclutched, the gear wheel 18 revolves upon 40 shaft 19 without transmitting power to either of the agitators.

Assuming the container is charged with the proper materials for a mixture of mortar, or the like, and that the motor is in 45 operation, the attendant throws the clutch lever to engage clutch member 21 with the clutch member 20 of wheel 18. This engagement instantly imparts rotation to shaft 19 and reversed rotation through gear wheels 23 and 24 to shaft 25, power being transmitted through the respective sprocket 50 transmission mechanisms to the shafts 7 and 7^a, so that the agitators shall revolve at the same speed in opposite directions, and thus stir and mix the materials in the container, it being noted that by reason of the angular 55 relation of the blades of one shaft with respect to the other, that the material is not only forced circularly within the container, but also from the ends toward the center 60 of the container, it being also noted that the bulk of the material as forced endwise by the blades of each set of agitators, enters the spaces between the blades of the other set so that all of the material is shunted 65 back and forth lengthwise of the con-

tainer as well as moved circularly therein. This treatment of the materials effects an exceedingly quick and thorough admixture and insures a correspondingly large output as compared with a machine in which agitators 70 revolve in the same direction. It will also be noted that as the blades collectively scrape, in effect, the entire inner surface of the container, and as there is no shaft impediment except near the ends of the container, practically the entire mixture can be quickly evacuated, so that without loss of time attendant upon scraping the interior of the container by hand, the latter can be recharged with materials for producing a new 75 80 batch of mortar or the like.

As a batch is completed, an attendant by means of handle 11, tips the container without arresting the operation of the agitators, one of the agitators while the container is 85 tilted, tending to feed the material to the other agitator, which through its reversed direction of rotation, tends to force the material out through the hopper.

From the above description, it will be apparent that we have produced a mixing machine possessing the features of advantage set forth in the statement of the object of the invention, and which are susceptible of modification in minor particulars without departure from the spirit and scope of the 95 appended claims.

We claim:

1. A mixing machine, comprising a cylindrical container having an opening at the top, a pair of aligned shafts projecting slightly through the end walls of the container axially of the cylindrical body thereof, means for simultaneously rotating said shafts in opposite directions, and blades carried by the shafts and extending longitudinally from a point midway the length of the body portion to the end walls respectively and rounded at their peripheral edges to scrape the interior of the body portion, and provided with inward projections at their outer ends for scraping the inner sides of the end walls, the said blades standing at angles to respectively force material in the 115 container, toward the center thereof, and one set of blades being disposed opposite the spaces between the blades of the other set.

2. A mixing machine, comprising a cylindrical container having an opening at the top, a pair of aligned shafts projecting slightly through the end walls of the container axially of the cylindrical body thereof, means for simultaneously rotating said shafts in opposite directions, arms extending 120 angularly from and rigid with the shafts, within the container, and blades extending longitudinally of the container from midway the length thereof to its end walls and fastened at points intermediate their length to 125 the outer ends of said arms, said blades be-

ing rounded at their peripheral edges to scrape the interior face of the body portion and provided with inward projections at their outer ends for scraping the inner faces of said end walls, and said blades extending at angles to respectively force material in the container toward the center thereof, the blades at each end being opposite the spaces between the other end.

In witness whereof we hereunto affix our ¹⁰ signatures.

OLIVER C. TALBOT.
ANDREW FLOOD.
